[57] ABSTRACT

An improved, dynamically balanced rotary engine comprising a cylindrical chamber having at least two intercommunicating, coplanar, substantially identical, sector-shaped (in cross section) sub-chambers which are equally spaced about and from the central longitudinal axis of the cylindrical chamber. At least two,

substantially identical rotors are mounted in the cylindrical chamber, with a rotor being mounted in each of the sub-chambers. The axis of rotation of the rotors are equi-spaced from each other and are equally, eccentrically spaced from the central longitudinal axis of the cylindrical chamber. Each rotor includes a wall portion having curved, peripheral surface which has a radius of curvature having a length substantially equal to, but slightly less than the length of the sub-chamber radius and which has a center of curvature located on the axis about which the rotor rotates.

Novel slider assemblies are positioned and extend between the adjacent leading and trailing ends of the peripheral surfaces of adjacent pairs of rotors.

The slider assemblies and the curved peripheral surfaces of the rotors define a continuous, generally annular working chamber about the cylindrical chamber and adjacent to the cylinder wall of the cylindrical chamber. The slider assemblies rotate with and move with respect to the rotors and prevent working fluid in the working chamber from passing radially inwardly between the leading and trailing ends of adjacent pairs of rotors.

When operated as an internal combustion engine, the improved engine may also include an interior chamber. The outer dimensions of this interior chamber are defined by the wall portions of the rotors and the slider assemblies. As the rotors rotate in the cylindrical chamber, the volume of this interior chamber varies so that this chamber can be utilized to pre-compress the working fluid prior to its introduction into the working chamber.

ROTARY ENGINE

This is a continuation of application Ser. No. 291,053 filed Sept. 21, 1972, and now abandoned.

BACKGROUND AND SUMMARY OF THE INVENTION

This invention relates to an improved rotary engine, and more particularly, to an improved, dynamically balanced, rotary engine, which may be utilized either as a motor or a pump and which, when used as a motor, may be powered by a variety of working fluids, such as steam or combustible gaseous mixtures.

One of the primary advantages of rotary engines is that, theoretically, the weight and overall size of these engines may be reduced, in relation to the weight and size of conventional crank-type engines of comparable power output. This reduction of weight and size is possible because many of the forces and force moments developed in conventional crank-type engines in transforming the reciprocating forces of the pistons into useful output work do not have to be present in rotary engines due to their design.

At the present, one of the most well known, commercially available rotary engines is the so-called "Wankel" internal combustion engine. The commercial attractiveness of the Wankel engine is primarily due to the fact that the weight and size of a marketable Wankel engine actually is significantly less than that of a comparable conventional crank-type engine. Moreover, the number of moving parts utilized in a marketable Wankel engine is less than the number required in a comparable conventional crank-type engine. This reduces the manufacturing costs and maintenance expenses of the Wankel engine as compared to conventional crank-type engines.

The Wankel engine does have disadvantages. It is essential for proper operation, that a seal be maintained at all times between the edges of the rotor and the cylinder wall of the housing so as to segregate the three chambers of the engine. Much work has been directed to developing a seal that is both effective and that has a relatively long life. At the present, however, these seals still present a problem. Furthermore, although vibration is not nearly the problem it is in conventional crank-type engines, the Wankel engine is subject to vibrations since during the operating cycle, combustion of the working fluid only occurs in one of the three chambers defined by the rotor and housing.

Like the Wankel engine, the overall size and weight of a rotary engine embodying the principles of my invention is significantly less than the size and weight of a conventional crank-type engine of comparable power output. Similarly, a much smaller number of moving parts is required in my improved rotary engine than is required in a comparable conventional crank-type engine.

In addition, the improved rotary engine of the present invention affords commercially significant advantages as compared to the Wankel engine. Unlike the Wankel engine, no seals are required between the rotor and the cylinder wall of the housing in my improved rotary engine. This not only reduces manufacturing costs and maintenance expenses, but also and more importantly, provides a large degree of design freedom with respect to the working chamber of the engine whereby the working chamber can be designed so as to maximize engine performance while minimizing emission of

pollutants. Furthermore, the tolerances required to be maintained for the cylinder wall of the housing and the rotors of my improved engine need not be as precise as those required in the Wankel engine since there is always a "gap" or space between the cylinder wall and the rotors during operation of the engine. This, of course, further reduces the manufacturing costs and maintenance expenses for my improved engine. Also, as a result of the novel configuration of the working chamber in my improved engine, the operation of the improved invention is dynamically balanced thereby minimizing engine vibration.

The foregoing advantages of the rotary engine of my invention results from engine design or geometry of the engine. More particularly, the improved engine of the present invention has a closed, cylindrical chamber defined in the engine housing by a continuous cylinder wall. The cylindrical chamber comprises at least two inter-communicating, coplanar, substantially identical sub-chambers that have sector shaped cross sections in a plane perpendicular to the longitudinal axis of the cylindrical chamber. The center axis of the sub-chambers are equi-spaced from each other and equally eccentrically spaced from the longitudinal axis of the cylindrical chamber, a distance less than the length of the sector or sub-chamber radii.

A plurality of substantially identical rotors are positioned in the cylindrical chamber, one in each of the sub-chambers, and are mounted for rotation about the center axis of their respective sub-chamber. The rotors have curved, radially outwardly facing peripheral wall portions that are disposed adjacent to the cylindrical wall of the housing. The center of curvature of the curved wall portions of the rotors is the center axis of their respective sub-chambers and their radius of curvature is substantially equal to but slightly shorter in length than the sub-chamber or sector radius. The working chamber in the cylindrical chamber is defined between the cylinder wall and these curved wall portions of the rotors.

In the preferred embodiment, novel slider assemblies are positioned between the leading and trailing ends of the each adjacent pairs of rotors and are utilized to prevent the leakage of working fluid from the working chamber radially inwardly between the ends of the rotor wall portions. The slider assemblies rotate with the rotors and move with respect to the adjacent pair of rotors.

Because of the difference in length between the radius of curvature of the rotor wall portions and sub-chamber or sector radii, and because of the absence of seals between the rotor wall portions and the cylinder walls, the working chamber has a generally annular shape, although the radial dimension of the working chamber varies as the rotors rotate. As a consequence of the configuration of the working chamber, the operation of the engine is dynamically balanced since the forces imposed by the working fluid on the rotors (e.g. during the combustion phase of the cycle) are substantially uniformly distributed throughout the annular working chamber.

When the improved engine of my invention is designed to function as an internal combustion engine, an interior chamber is formed within the cylindrical chamber, and its outer dimensions are defined by the wall portions of the rotors and the slider assemblies. As a result of the eccentrical mounting of the rotors, the volume of this interior chamber varies as the rotors rotate

in the cylindrical chamber. The interior chamber is utilized to pre-compress the combustible working fluid or gaseous mixture prior to the introduction of the working fluid into the working chamber.

As noted above, the unique design or geometry of my novel, improved rotary engine affords commercially important advantages not only with respect to conventional crank-type engines but also with respect to the Wankel rotary engine. Accordingly, it is a primary object of the present invention to provide an improved, dynamically balanced rotary engine which may be utilized either as a motor or pump and which incorporates the principles of this novel engine design or geometry.

This and other objects and advantages of the present invention will be apparent to those skilled in the art from a reading of the following specification of this invention and a review of the accompanying drawings.

BRIEF DESCRIPTION OF THE DRAWINGS

FIGS. 1-4 are diagrammatic views illustrating the design or geometry of a two sub-chamber, cylindrical chamber for an improved rotary engine which embodies the principles of the present invention.

FIGS. 5-9 are diagrammatic views illustrating the relationships between the two sub-chamber, cylindrical chamber shown in FIGS. 1-5 and the rotors which embody the principles of the present invention.

FIGS. 10-15 are diagrammatic views illustrating various positions of a pair of rotors as they rotate in a two sub-chamber, cylindrical chamber in an improved rotary engine which embodies the principles of the present invention.

FIGS. 16-20 are diagrammatic views illustrating the design or geometry of a three sub-chamber, cylindrical chamber for an improved rotary engine which embodies the principles of the present invention. FIGS. 21-26 are diagrammatic views illustrating various positions of three rotors as they rotate in a three sub-chamber, cylindrical chamber in an improved rotary engine which embodies the principles of the present invention.

FIGS. 27-32 are diagrammatic views illustrating various positions of four rotors as they rotate in a four sub-chamber, cylindrical chamber in an improved rotary engine of the present invention.

FIG. 33 is an exploded, perspective view of the components of the housing and the valve plate which are utilized with the preferred embodiment of the rotary engine of the present invention.

FIG. 34 is an exploded, perspective view of the rotor assemblies, slider assemblies and associated parts which are utilized with the preferred embodiment of the rotary engine of the present invention.

FIG. 35 is a vertical cross-sectional view, of the assembled assemblies and parts shown in FIG. 34, taken in a plane perpendicular to the central longitudinal axis of the preferred embodiment of the improved rotary engine of the present invention.

FIG. 36 is a cross-sectional view, taken along the section line 36-36 in FIG. 35.

FIG. 37 is a vertical cross-sectional view of the preferred embodiment of the improved rotary engine of the present invention, taken in a plane including the central longitudinal axis of the engine.

FIG. 38 is a vertical cross-sectional view taken along the section line 38-38 in FIG. 37.

FIG. 39 is a vertical cross-sectional view taken along the section line 39-39 in FIG. 37.

FIG. 40 is a side plan view of the inner side of the manifold cover plate utilized with the preferred embodiment of the improved rotary engine of the present invention.

FIG. 41 is a side plan view of the valve plate utilized with the preferred embodiment of the improved rotary engine of the present invention.

FIG. 42 shows the preferred embodiment of the improved rotary engine of the present invention coupled with another identical rotary engine.

FIG. 43 is a vertical cross-sectional view similar to that shown in FIG. 38 except that the rotor assemblies are rotated 90° from the position shown in FIG. 38.

FIG. 44 is a vertical cross-sectional view similar to that shown in FIG. 38 except that the rotor assemblies are rotated 180° from the position shown in FIG. 38.

FIGS. 45-52 are diagrammatic views illustrating the operation of the improved engine shown in FIGS. 33-44 when the engine operates as a two-cycle engine.

FIGS. 53-60 are diagrammatic views illustrating the operation of the improved engine shown in FIGS. 33-44 when the engine operates as a four-cycle engine.

FIGS. 61 and 62 diagrammatically illustrate the various phases in the cycle of operation, with respect to the angular position of the rotor assemblies, for the improved engine shown in FIGS. 33-44 when the engine is operating as a two-cycle and four-cycle engine, respectively.

FIGS. 63 and 64 diagrammatically illustrate the working fluid induced forces and force movement which act on the rotor assemblies in the improved engine shown in FIGS. 33-44.

FIG. 65 graphically illustrates the relationships between the volumes of the working chamber and interior chamber, with respect to the angular position of the rotor assemblies, in the improved engine shown in FIGS. 33-44.

FIG. 66 graphically illustrates the assumed pressures of the working fluid in the working chamber and interior chamber, with respect to the angular position of the rotor assemblies, in the improved engine shown in FIGS. 33-44.

FIGS. 67-76 diagrammatically illustrate various modified rotor assemblies which may be utilized with the improved rotary engine of the present invention.

Throughout the various figures of the drawings, the same numerals will be used to designate the same or substantially the same parts. Moreover, when the terms "right," "left," "right end," "left end," "inner," and "outer" are used herein, it is to be understood that these terms have reference to the structure shown in the drawings as it would appear to a person viewing the drawings.

DESCRIPTION OF THE PREFERRED EMBODIMENTS

FIGS. 1-32

As noted above, the improved engine of the present invention includes a cylindrical chamber, shown generally at 1. The basic design or geometry of a two sub-chamber, cylindrical chamber 1, is diagrammatically illustrated in FIGS. 1-4. More specifically, the cylinder chamber 1, as shown in FIG. 1, includes two sub-chambers 2 and 3. The centers or longitudinal center lines 4 and 5 of the sub-chambers 2 and 3 are equi-spaced from the center of longitudinal center line 6 of the cylindrical chamber 1. The sub-chamber 2 is formed or

generated by rotating a radius 7 about the center 4, and the sub-chamber 3 is formed or generated by rotating a radius 8 about the center 6. The lengths of the radii 7 and 8 are equal, and the sub-chambers 2 and 3 have identical, generally sector-shaped cross sections. The distance between the centers 4-6 and the centers 5-6 are equal and are less than the length of the radii 7 and 8.

FIGS. 5-9 illustrate further details of the design or geometry of the cylindrical chamber 1 of the present invention. The cylindrical chamber 1 is shown in FIG. 5 embodied in a housing 9, with the chamber 1 being defined by the continuous cylinder wall 10 of the housing 9. In FIG. 6, a pair of substantially identical rotor assemblies 11 and 12 embodying the principles of the present invention are shown positioned within the housing 9 for a rotation in the cylindrical chamber 1. The rotary assembly 11 is positioned in cylindrical chamber 1 so that it rotates about the center 4 of sub-chamber 2. The rotor assembly 12 is positioned in cylindrical chamber 1 so that it rotates about the center 6 of sub-chamber 3. The curved, radially outwardly facing surfaces 13 and 14 of the rotor assemblies 11 and 12 have their centers of curvature located at the centers 4 and 5, respectively, and each have a maximum radius of curvature of a length substantially equal to, but slightly less than the length of the radii 7 and 8 so that there is a slight gap or space between the surfaces 13 and 14 and the cylinder wall 10 of the housing 9. In FIG. 7, the cross-sectioned area represents, of course, the area of the chamber 1, and as noted above, is substantially the area "swept" by the rotor assemblies 11 and 12 during one complete rotation of these assemblies. In FIG. 8, the cross-sectioned area represents the area of the cylindrical chamber 1 which is always covered by the rotor assemblies 11 and 12. The cross-sectioned area shown in FIG. 9 represents the maximum area of the working chamber 15 in the cylindrical chamber 1, with the working chamber 15 being defined as the portion of the chamber 1 between the curved surfaces 13 and 14 of the rotor assemblies 11 and 12 and the cylinder wall 10 of the housing 9.

FIGS. 10-15 diagrammatically illustrate the various positions of the pair of rotor assemblies 11 and 12, as these assemblies rotate about the centers 4 and 5, respectively, in the cylindrical chamber 1 and move with respect to each other. During such rotation, the base portions 16 and 17 of the assemblies 11 and 12 are always held in contact and to permit this, the rotor assemblies 11 and 12 must be constructed so that the lengths of the curved surfaces 13 and 14 can vary as the assemblies 11 and 12 rotate. Alternatively, rotor assemblies having a fixed length could be utilized but then additional means, such as the slider assemblies described hereinafter, must also be used. Moreover, during rotation of the rotor assemblies 11 and 12, the plane which includes the base portions 16 and 17 always extends through the center 6 of the cylindrical chamber 1.

In FIG. 10, the rotor assembly 11, which rotates about the center 4, is shown positioned in the sub-chamber 2 while rotor assembly 12, which rotates about the center 5, is shown positioned in sub-chamber 3. When thus positioned, the rotor assemblies 11 and 12 substantially "fill" the cylindrical chamber 1 and the volume of the working chamber 15 is at a minimum and is limited to the annular gap or space between the curved surfaces 13 and 14 and the cylinder wall 10. In

FIG. 13, the rotor assemblies 11 and 12 have rotated through an angle of 180° relative to their position in FIG. 10. When the rotor assemblies 11 and 12 are positioned as shown in FIG. 13, the working chamber 15 achieves its maximum volume.

FIGS. 16-20 diagrammatically illustrate the design and geometry of a three sub-chamber cylindrical chamber 21 which embodies the principles of the present invention. More specifically, the cylindrical chamber 21 includes three substantially identical sub-chambers 22, 23 and 24, that are formed or generated by rotating a radii, shown at 25, 26 and 27, about centers 28, 29 and 31, respectively. The radii 25, 26, and 27 are of equal length and the centers 28, 29 and 31 are equi-spaced from each other and equally eccentrically spaced from the center 32 of the cylindrical chamber 21. The distance between the center 32 and the centers 28, 29 and 31, respectively, is shorter than the length of the radii 25, 26 and 27.

FIGS. 21-26 diagrammatically illustrate the various positions of three substantially identical rotor assemblies 33, 34 and 35 as these assemblies rotate in the cylindrical chamber 21 and move with respect to each other. The rotor assemblies 33, 34 and 35 are positioned in chamber 21 for rotation about the centers or axes 28, 29 and 31, respectively, of the sub-chambers 22, 23 and 24. Like the assemblies 11 and 12, each of the rotor assemblies 33, 34 and 35 has a curved radially outwardly facing surface 36, 37 and 38, respectively, which have their centers of curvature located at the centers 28, 29 and 31, respectively. The radii of curvature of the surfaces 36, 37 and 38 are equal and the maximum length of these radii of curvature is substantially equal to, but slightly smaller than the length of the radii 25, 26 and 27, so that when the rotors are positioned within the chamber 21, there is always an annular gap or space between these curved surfaces 36, 37 and 38 and the continuous cylinder wall 10 of the chamber 21. In FIG. 21, the rotor assemblies 33, 34 and 35 are shown positioned in the sub-chambers 22, 23 and 24 so that they substantially "fill" the cylindrical chamber 21 and so that the volume of the working chamber 16 is at a minimum i.e. consists only of the annular gap or space between the rotor surfaces 36, 37 and 38 and the cylinder wall 10. In FIG. 24, the assemblies 33, 34 and 35 are shown rotated 180° from the position shown in FIG. 21 and when the assemblies are so positioned, the working chamber 15 achieves its maximum volume. Like assemblies 11 and 12, the base portions of the rotor assemblies 33, 34 and 35 are always held in contact during rotation of the assemblies in the cylindrical chamber 21.

FIGS. 27-32 are generally similar to FIGS. 21-26 except that the former diagrammatically illustrates the various positions of four substantially identical rotor assemblies 41, 42, 43 and 44 as these assemblies rotate in a four subchamber cylindrical chamber 45. The cylindrical chamber 45 includes four substantially identical sub-chambers 46, 47, 48 and 49. The four rotor assemblies, 41, 42, 43 and 44 are positioned within the sub-chambers of 46, 47, 48 and 49, respectively, for rotation about the sub-chamber centers 51, 52, 53 and 54. As in cylindrical chambers 1 and 21, these sub-chamber centers are equally spaced from each other and from the center 55 of the cylindrical chamber 45. Each of the rotors 41-44 have curved radially outwardly facing surfaces 56, 57, 58 and 59, respectively, which have their centers of curvature located at the

sub-chamber centers 51, 52, 53 and 54, respectively. The radii of curvature of the surfaces 56-59 are equal, and the length of these radii are substantially equal to, but slightly shorter than, the length of the radii which define the sub-chambers 46-49 so that there is a generally annular gap or space between these outer surfaces 56-59 and the cylindrical wall 10 of the cylindrical chamber 45. Like assemblies 11 and 12 and assemblies 33-35, the base portions of the rotor assemblies 41-44 are always held in contact during rotation of the assemblies in the cylindrical chamber 45.

In FIG. 27, the rotor assemblies 41-44 are shown positioned in the sub-chambers 46-49, respectively, so that the rotor assemblies substantially "fill" the cylindrical chamber 45 and the volume of the working chamber 15 is at a minimum and consists only of the generally annular gap or space between the curved surfaces 56-59 and the cylinder wall 10. As the rotor assemblies 41-44 rotate in the chamber 45 from the position shown in FIG. 27, the volume of the working chamber 15 increases. When the assemblies have rotated through an arc of 180 to the position shown in FIG. 30, the working chamber 15 is at its maximum volume.

FIGS. 33-66

Referring now to FIGS. 33-44, an improved rotary engine embodying the principles of the present invention is shown generally at 70. The engine 70 is the preferred embodiment of my invention, and is designed as an internal combustion motor. As hereinafter explained, as shown in FIG. 42, the engine 70 is usually connected, in tandem, with one or more similar engines in normal usage.

Basically, the engine 70 comprises a housing assembly, shown generally at 72 in FIG. 33; and a movable assembly, shown generally at 74 in FIG. 34, which is adapted to be disposed within the housing assembly 72. The housing assembly 72 includes a generally annular, center housing 76. The exterior surface of the housing 76 includes a plurality of integral fins to facilitate air cooling. A pair of diametrically opposed, internally threaded, projections 77 are also formed on the annular exterior surface of the housing 76. These projections 77 communicate with the interior of the housing and are adapted to receive conventional spark plugs such as shown in FIG. 38. A continuous cylinder wall 78 in the center housing 76 defines the periphery of a centrally disposed, cylindrical chamber 80.

The cylindrical chamber 80 has the same design or geometry as the chamber 1 described hereinabove and includes an upper and lower substantially identical, subchamber 81 and 83, best shown in FIG. 38. The central axis of these sub-chambers are parallel to the central longitudinal axis of the cylindrical chamber 80 and are equally, eccentrically spaced, on diametrically opposite sides, from the central longitudinal axis of the chamber 80. In a plane perpendicular to the central longitudinal axis of the chamber 80, the sub-chambers 81 and 83 have a generally sector-shaped cross section, with the sector radii of the two sub-chambers being equal in length. The sub-chambers 81 and 83 intercommunicate, with the distance from the central longitudinal axis of the cylindrical chamber 80 to the axis of the sub-chamber 81 or 83 being less than the length of the sector radius of the sub-chambers. The cylindrical chamber 80 extends from the end of the housing 76 to the other.

A cover plate 82 is mounted adjacent to the left side of the center housing 76 so as to block or close the left end of the cylindrical chamber 80. The cover plate 82 includes a plurality of integral cooling fins on its outer or left-hand surface. A centrally disposed aperture 84 and a second eccentrically disposed, aperture 85 are formed in the plate 82. The central axis of the aperture 84 is coaxial with the central longitudinal axis of the chamber 80 and is parallel to but spaced from the axis of aperture 85. The inner or right-end face 86 of the plate 82 is machined so as to provide a continuous sealing surface.

A manifold cover plate 88 is mounted adjacent to the other or right-hand end of the center housing 76 so as to lock or close the other or right end of the cylindrical chamber 80. The outer or right-hand surface of the plate 88 includes a plurality of cooling fins. As best seen in FIG. 37, a steel insert disk 89 is casted into the inner or left-hand surface 91 of the plate 88. A rotatable valve plate 90, hereinafter described, is positioned between the right end of the cylindrical chamber 80 and the surface 91 of the end plate 88, with the insert 89 serving as a bearing surface for the valve plate 90. An inlet manifold 92 is formed on the annular surface 25 of the end plate 88. A pair of diametrically opposed exhaust manifolds 94 are also formed on the annular surface of the plate 88 at points spaced from the manifold 92. A centrally disposed aperture 96 and a second, eccentrically disposed aperture 97 are formed in the end plate 88. The central axis of the aperture 96 is coaxial with the central, longitudinal axis of the cylindrical chamber 80 and is parallel to the central axis of the aperture 97. The apertures 85 and 97 are equi-spaced from and are on diametrically opposite sides of the central longitudinal axis of the chamber 80.

The end plates 82 and 88 have a plurality of aligned, bolt receiving ears 98 formed thereon. The plurality of bolts 100 extend through these aligned pairs of ears and together with nuts 102 are used to secure the end plates 40 82 and 88 tightly against the center housing 76. A pair of annular, sealing gaskets 104 and 106 are disposed between the peripheral surface of the end plate 82 and the one left side of the housing 76 and between the peripheral surface of the end plate 88 and the right side of 45 the housing 76, respectively, when the engine 70 is assembled.

Referring now to FIGS. 34-37, the assembly 74 includes a rotatable shaft 108 which has splines formed in its right end 110, in its left end 112 and in its center portion 114. The central longitudinal axis of the shaft is coaxial with the central longitudinal axis of the cylindrical chamber 80. The splined ends 110 and 112 of the shaft 108 extend through the central apertures 84 and 50 96 in the cover plates 82 and 88, respectively, so that the splined ends 110 and 112 project beyond the outer surfaces of the plates 82 and 88 as best shown in FIG. 37.

A pair of cylindrical shaft bearings 116 are positioned on the shaft between the center portion 114 and 55 the ends 110 and 112. A shoulder 118 is integrally formed on the inner ends of the bearings 116.

A pair of excenter members 120 and 121 are mounted on the outer peripheral surfaces of the bearings 116, with the shoulders 118 of the bearings 116 preventing inwardly directed, relative movement between the excenter members 120 and 121 and the shaft 108. The bearing members 116, however, do permit relative rotative movement between the shaft 108 and

the excenter members 120 and 121 which, as described below, are not permitted to rotate. A spacer sleeve 123 is mounted on the shaft 108 between the inner end of the member 120 and the center splined portion 114 of the shaft 108 for the purpose of assisting in maintaining the correct axial alignment of the components of the assembly 74.

Since the members 120 and 121 are structurally and functionally identical, only excenter member 120 is described in detail herein. The excenter member 120 includes a threaded outer end 122 and has an eccentrically mounted circular flange 124 formed adjacent to its inner end 125. The members 120 and 121 are mounted on the shaft 108 so that their eccentric flanges 124 are diametrically, oppositely disposed and so that the flange of the member 120 is disposed in sub-chamber 81 and the flange of the member 121 is disposed in sub-chamber 83. An aperture 126 is drilled in each flange 124. As shown in FIG. 37, the central axis of the aperture 126 in the member 120 is coaxial with the central axis of the aperture 97 in end plate 88, while the central axis of the aperture 126 in member 121 is coaxial with the aperture 85 in the end plate 82. A dowel pin 127 is positioned in and extends between the aperture 97 and the aperture 126 in the member 120. A dowel pin 128 is positioned in and extends between the aperture 85 and the aperture 126 in the member 121. The pins 127 and 128 hold the excenter members 120 and 121 against rotating in the housing assembly 72.

As seen in FIG. 37, the threaded outer ends 122 of the excenter members 120 and 121 extend out through the central apertures 84 and 96 in the end plates 82 and 88, respectively. A pair of lock nuts 131 are threaded onto these outer ends 122 and hold the members 120 and 121 against axial movement.

A pair of conventional bearing rings 129 and 130 are press fit about the outer periphery of eccentric flanges 124 of the excenter members 120 and 121, respectively.

A pair of rotor assemblies 132 and 133 are rotatably mounted on the eccentric flanges 124 of the excenter members 120 and 121, respectively. Since the assemblies 132 and 133 are structurally and functionally identical, only rotor assembly 132 is described in detail herein.

The rotor assembly 132 includes a curved wall 134, a radially extending neck 136 and a base 138. The base 138 includes a central aperture 140, the central axis of which is coaxial with the central axis of the eccentric flange 124 of the member 120 which in turn is coaxial with the central axis of the sub-chamber 81. The dimension of the aperture 140 is selected such that it snugly fits about the flange 124, and the bearing ring 129. However, the "fit" between the aperture 140 and the ring 129 and flange 124 does permit the assembly 132 to freely rotate about the relatively fixed flange 124 and ring 129 and thus, about the central axis of the sub-chamber 81.

A counterweight 141 is secured to the radial, inner end 142 of the base 138 and is used to counterbalance the rotor assembly 132. A slide bar 144 is mounted on each of the sides of the base 138 by a tongue and groove connection.

The neck 136 of the assembly 132 is integrally connected, at its radial inner end, with the base 138 and, at its radial outer end, with the wall 134. As best shown in FIG. 34, the necks 136 of the assemblies 132 and 133

are connected to the side of the wall 134 adjacent to the end covers 82 and 88.

The wall 134 has a generally U-shaped cross section with the open and the "U" facing radially inwardly. A curved, radially outwardly facing surface 146 is formed on the wall 134. This surface has its center of curvature located on the axis about which the assembly 132 rotates, i.e. the central axis of the eccentric flange 124 of the member 120. Also as noted above, the length of the radius of curvature of the surface 146 is substantially equal to, but slightly less than, the length of the sector radius of the sub-chamber 81 whereby there is always a gap or space between the surface 146 and the cylinder wall 78 of, for example, on the order of several thousandths of an inch.

Grooves 148 are formed in the side of the wall 134. Rotor sealing strips 150 are positioned in the grooves 148 and are used to form running fluid seals between the left side of the wall 134 and the inner machined surface 86 of the end plate 82 and between the right side of the wall 134 and the left-hand, inner surface of the valve plate 90. Springs 152 bias the strips 150 into sealing contact with the end plate 82 or the valve plate 90, as the case may be.

Substantially flat surfaces 154 are formed on the ends of the wall 134. The planes of these surfaces 154 are generally parallel to a plane of the side of the neck 136. Sealing bars 156 are secured across the lower edges of these surfaces 154.

A slider assembly, shown generally in 158, is positioned within the cylindrical chamber 80 and generally between the two rotor assemblies 132 and 133. As described more fully hereinafter, the slider assembly 158 is mounted on the shaft 108 so that it may rotate with the rotor assemblies 132 and 133. However, because the axis of rotation of the assembly 158 is coaxial with the longitudinal axis of the shaft 108, there is also relative sliding motion between the assembly 158 and the assemblies 132 and 133 during rotation.

The slider assembly 158 includes a driver assembly 160 consisting of a pair of parallel plates 162 and 164 that are spaced apart in the direction parallel to the longitudinal axis of shaft 108. Rollers 166 and 168 are journaled, for rotation, between the ends of the plates 162 and 164. A sleeve 170 is secured to and extends between the plates 162 and 164 adjacent to their center. The sleeve 170 includes internal splines which are adapted to mate with the spline portion 114 of the shaft 108 so that when the driver assembly is mounted on the shaft 108, as shown in FIG. 36, rotation of the assembly 160 results in similar rotation of the shaft 108 and vice versa.

A pair of sliders 172 and 173 cooperate with the drive assembly 160. Since the sliders 172 and 173 are structurally and functionally identical, only the slider 172 will be described in detail herein. The slider 172 has a generally offset U-shape and includes a pair of spaced apart heads 174, a central base 176, and a pair of arms 178 which integrally inter-connect the heads 172 and with the ends of the base 176. Each of the heads 174 of the slider 172 includes a curved, outer surface 180 whose curvature generally conforms to the curvature of the surface 146 of the rotor assembly 132. The heads 174 also include inner, substantially flat surfaces 182 which face each other and which are in sliding, surface-to-surface contact with the flat end surfaces 154 formed on the wall 134 of the rotor assembly 132. The sealing bars 156 are utilized to prevent work-

ing fluid from leaking between the adjacent surfaces 154 and 182. Each of the heads 174 also includes a substantially flat, bottom surface 184 which is adapted to be in a sliding, surface-to-surface contact with the corresponding bottom surface 184 of the adjacent head portion 174 of the slider 173.

The base 176 of the slider 172 has a pair of substantially flat spaced apart surfaces 186 formed thereon which face in the opposite direction to the bottom surface 184 on the head 174 and which are in roller-to-surface contact with the rollers 166 and 168. This roller-to-surface contact permits the sliders 172 and 173 to move relative to the driver assembly 160 and thus relative to the rotor assemblies 132 and 133 during operation of the engine 70. As seen in FIGS. 34 and 38, the surfaces 186 on the slider 172 contact the bottoms of the rollers 166 and 168; whereas, the surfaces 186 on the slider 173 contact the tops of the rollers 166 and 168.

Two pair of coplaner surfaces 188 are formed on the upright facing portions of the arms 178. The distance between these facing pairs of surfaces 188 is substantially equal to the width of the base 138 of the assembly 132 so that the surfaces 188 are in sliding surface-to-surface contact with the slide bars 144 mounted on the sides of the base 138.

Each of the heads 174 have a generally T-shaped groove 190 formed in each of its sides. Generally flat, L-shaped seal members 192 are positioned adjacent to the sides of the heads 174 and form a fluid seal between the left-hand side of the heads 174 and inner surface 86 of the end plate 82 and between the right-hand side of the heads 174 and inner surface of the valve plate 90. The members 192 include a base flange 194 which extends into the horizontal portion of the T-shaped groove 190. Springs 196 are positioned in the vertical portion of the grooves 190 and bias the members 192 outwardly into sealing with end plate 82 or the valve plate 90, as the case may be.

The right-hand sides of the four members 192, which are positioned on the right side of the heads 174 of the slider assemblies 172 and 173, include projections or flanges 198 which extend to the right beyond the plane of the body of the members 192. As best shown in FIG. 41, the left-hand face of the valve plate 90 includes a pair of diametrically opposed grooves 202 and 204. Each of the grooves 202 and 204 are spaced and are of sufficient width, in a circumferential direction so that the two projections 198, which are on the members 192 carried by a pair of adjacent upper and lower heads 174 of the sliders 172 and 173, can fit within a groove 202 or 204, while the two projections 198, which are on the members 192 carried by the opposite pair of adjacent upper and lower heads 174, then can fit within the other groove 202 or 204. This fit between the valve plate 90 and the assembly 158 causes the valve plate 90 to rotate with the assembly during operation of the engine.

As noted above, when the rotor assemblies 132 and 133 and the slider assembly 158 are positioned within the cylindrical chamber 80, the outer surfaces 146 of the walls 134 of the rotor assemblies 132 and 133 and the outer surfaces 180 of the heads 174 of the sliders 172 and 173 are dimensioned so that they are always radially spaced from the cylindrical wall 78 thereby defining a working chamber, shown generally at 210, about the periphery of the chamber 80. As best shown by a comparison of FIGS. 38, 43 and 44; the volume of

the working chamber 210 varies as the rotor assemblies 132 and 133 rotate in the chamber 80. Moreover, during such rotation, the sliders 172 and 173 move relatively with respect to each other in a plane which includes the central longitudinal axis of the shaft 108, and with respect to the assemblies 132 and 133.

Also as noted above, an interior chamber 212 is formed within the chamber 80. The outer dimensions of this chamber 212 are defined by the walls 134 of the assemblies 132 and 133 and the heads 174 of the slider assembly 158. The interior chamber 212 is completely separate or segregated from the working chamber 210. As shown by a comparison of FIGS. 38, 43 and 44 the volume of the interior chamber 212 also varies during rotation of the assemblies 132 and 133, but inversely as to the volume of the working chamber 210. FIG. 65 graphically illustrates the relationship between the volumes of the chambers 210 and 212 versus the angular position of the shaft 108, assuming that the zero degree position of the shaft occurs when the engine 70 is positioned as shown in FIG. 38. (In FIG. 65, the solid line curve represents the volume of the chamber 210, whereas, the dotted line curve represents the volume of the chamber 212.) As a result of the relationship of the volumes of the chambers 210 and 212, the interior chamber 212 can be and is utilized to pre-compress the working fluid or combustible gaseous mixture prior to its being drawn into the working chamber 210.

The operation of the engine 70 is controlled by the design of the valve plate 90 and more precisely, by the cooperation between the valve plate 90 and the inner, left-hand surface 91 of the end plate 88. The inner face 91 of the end plate 88 has a plurality of chambers casted therein. Referring now to FIG. 40, the face 91 includes an inlet chamber 216 which is spaced radially outwardly from the central aperture 96 and which communicates by means of passage 218, with the inlet manifold 92. Spaced radially outwardly from the chamber 216 and angularly with respect to the chamber 216 are a pair of diametrically opposed, transfer chambers 220 and 222. These transfer chambers 220 and 222 are not connected with any passage. A pair of exhaust chambers 224 and 226 are spaced radially outwardly from the chambers 220 and 222. The chambers 224 and 226 are connected with the adjacent exhaust manifolds 94 by means of passages 228 and 230, respectively.

Two dotted circular rings 234 and 236 are shown in FIG. 40. These rings 234 and 236 do not represent any physical structure, but do indicate the path of travel of the seals 150 carried by the right sides of the walls 134 of the rotor assemblies 132 and 133, with the ring 234 representing the path of the seal 150 on the assembly 132 and with ring 236 representing the path of the seal 150 on the assembly 133. The ring 234 passes radially outwardly of the exhaust port 224 and intersects the transfer chamber 222 while the ring 236 passes radially outwardly of the exhaust chamber 226 and intersects the transfer chamber 220.

The valve plate 90, as best shown in FIGS. 39 and 41, consists of a relatively thin, annular disk which has a central aperture 236 therein. The plate 90, as noted above, rotates with the slider assembly 158 as a result of the cooperation between the grooves 202 and 204 and the projections 198 on the right-hand members 192 carried by the slider heads 174. The size of the central aperture 236 is selected so that the aperture fits about an inwardly directed hub 238 which, in turn, is formed on the end plate 88 about the central aperture

96. As shown in FIG. 37, the central axis of the aperture 236 is coaxial with the central longitudinal axis of the shaft 108 and the aperture 96.

An inlet port 240 is formed in the plate 90 at a location spaced radially outwardly from the aperture 236. The inner and outer radial dimensions of the port 240 are the same as the comparable dimensions of the chamber 216. The circumvential length of the port 240 is likewise equal to the circumvential length of the chamber 216. Three transfer ports 242, 244 and 246 are formed in the plate 90 generally along a circle spaced radially outwardly from the port 240. Only ports 242 and 244 actually function to transfer working fluid during the operation of the engine, as hereinafter described, and the port 246 is included in the valve plate for the purpose of balance. The ports 242-246 are identical in shape and size and they, as a group, extend almost completely around the plate 90, as shown in FIG. 41. While the radial inner dimension of the ports 242-246 is equal to the radial inner dimension of the transfer chambers 220 and 222, the overall, radial width of the ports 242-246 is slightly less than the overall, radial width of the transfer chambers 220 and 222.

A pair of diametrically opposed secondary transfer ports 248 and 250 are also formed in the plate 90 and are spaced radially outwardly from the ports 242-246. The ports 248 and 250 are identical in size and shape and have overall radial width less than the overall radial width of the chambers 220 and 222. The radial outer dimensions of the ports 248 and 250 are, however, equal to the radial outer dimensions of the transfer chambers 220 and 222. The radial inner dimensions of the ports 248 and 250 and the radial outer dimensions of the ports 242 and 244 are selected so that the seals 150 pass, and form a seal, between the ports 242 and 248 and between ports 244 and 250 during a portion of the cycle of operation of the engine 70 so as to form a seal therebetween.

A pair of diametrically opposed identical ports 252 and 254 are formed in the plate 90 and are spaced radially outwardly from the ports 248 and 250. The inner and outer radial dimensions of the ports 252 and 254 are equal to the comparable dimensions of the exhaust chambers 224 and 226. Likewise, the circumvential length of the ports 252 and 254 are equal to the circumvential length of the chambers 224 and 226.

The operation of the engine 70 can best be described with reference to FIGS. 45-52 which diagrammatically illustrate various positions of the rotor assemblies 132 and 133 during a cycle of operation. When the components of the engine are positioned as shown in FIG. 45, a combustible gaseous mixture or working fluid is being drawn into the interior chamber 212 while the working fluid in the working chamber 210 is being compressed. In this position, the valve port 240 is in alignment or in overlapping relationship with the chamber 216 so that the working medium can be drawn in through the inlet manifold 92 through the passage 218 and thereafter pass from the chamber 216, through the port 240, into the interior chamber 212. At the same time, none of the other ports in the valve plate 90 are aligned with any other chamber in the end plate 88. Thus, there is no fluid communication between the working chamber 210 and the interior chamber 212.

In FIG. 46, working fluid is still being drawn into the interior chamber 212 while the working fluid in the working chamber 210 is being further compressed. Again in FIG. 46, the port 240 in plate 90 in alignment

with the chamber 216 in the end plate 88, but none of the other ports and chambers are in functioning alignment.

When the components of the engine 70 have rotated to the position shown in FIG. 47, combustion of the working fluid in chamber 210 has occurred, and the induction of working fluid into the interior chamber 212 has been completed. Thus, the inlet port 240 has just moved out of alignment or overlap relationship with the chamber 216. It should be noted that while the pairs of transfer ports 242-248 and 244-250 may come into alignment or in an overlap relationship as the components of the engine 70 move from the position shown in FIG. 47 to that shown in FIG. 48, this alignment does not result in any transfer of the working fluid from the interior chamber 212 to the working chamber 210 due to the fact that the seals 150 are disposed radially outwardly from the outer radial dimensions of the ports 248 and 250.

When the components of the engine 70 are in the position shown in FIG. 48, combustion and expansion of the working fluid in the chamber 210 is continuing, while the pre-compression of the working fluid in the interior chamber 212 is beginning. When the components of the engine are shown in FIG. 48, none of the valve ports in the plate 90 are in alignment with their corresponding chambers in the end plate 88. As the components of the engine rotate from the position shown in FIG. 48 to that shown in FIG. 49, expansion of the working fluid in the working chamber 210 still continues, while pre-compression of the working fluid in the interior chamber 212 also continues.

As noted above, the volume of the working chamber 210 is increasing as the components move from the position shown in FIG. 47 to that shown in FIG. 50; while the volume of the interior chamber is decreasing during the same time, and the relationship between the volumes of the working chamber 210 and the interior chamber 212, relative to each other, is graphically shown in FIG. 65. From FIG. 65, and as noted above, the volume of the working chamber 210 is at a minimum, and the volume of the interior chamber at a maximum when the rotor assemblies 132 and 133 are positioned as shown in FIG. 38, the zero-degree position shown in FIG. 65. Furthermore, the volume of the working chamber 210 is at a maximum while the volume of the interior chamber 212 is at its minimum after the rotor assemblies have rotated 180 or rotated from the position shown in FIG. 38 to the position shown in FIG. 44.

When the components of the engine 70 move to the position shown in FIG. 50, the working fluid is being exhausted from the working chamber 210 while the working fluid in the interior chamber 212 continues to be compressed. In the FIG. 50 position, the ports 252 and 254 are in alignment or an overlap relationship with the chambers 224 and 226 so that the fluid in chamber 210 can pass from the chamber 210 and through the ports 252 and 254, the chambers 224 and 226, and the passages 228 and 238 to the exhaust manifolds 94. When the components of the engine are rotated to the position shown in FIG. 51, pre-compressed working fluid is transferred from the interior chamber 212 to the working chamber 210 while the combusted working fluid is still being exhausted from the chamber 210. In the FIG. 51 position, the exhaust ports 252 and 254 are still in alignment or in overlap relationship with the exhaust chambers 224 and 226, while the pairs of

transfer ports 242-248 and 244-250 are just coming into alignment or into overlap relationship with the transfer chambers 220 and 222. Unlike when the components were positioned as shown in FIG. 47, the seals 150 are now disposed between the pairs of ports 242-248 and between the pairs of ports 244-250 so that the transfer ports can function to transfer the pre-compressed working fluid in the interior chamber 212 to the working chamber 210. These seals 150 still do function, however, to prevent the leakage of working fluid between these two chambers 210 and 212 along or between the sides of the walls 134 and the plate 90.

When the components of the engine 70 are moved to the position shown in FIG. 52, the transfer of working fluid from the interior chamber 212 to the working chamber 210 continues. However, in the FIG. 52 position, the exhaust ports 252-254 have moved out of alignment or an overlap relationship with the chambers 224 and 226. As the components of the engine 70 move from the position shown in FIG. 52 to the position shown in FIG. 45, the cycle of operation begins over again, with the inlet port 240 coming into alignment or registry with the inlet chamber 216.

FIG. 61 diagrammatically illustrates the phases of the cycle of operation of the engine 70 with respect to the angular disposition of the shaft 108. The outer ring 251 represents the phases which occur in the working chamber 210, while the inner ring 253 represents the phase which occur in the interior chamber 212. FIG. 61 merely summarizes the action which has been described hereinabove in relation to FIGS. 45-52.

As will be apparent from the foregoing description of the operation of the engine 70, the pressure of the working fluid in the working chamber 210 and in the interior chamber 212 varies during a cycle of operation. FIG. 66 diagrammatically illustrates the assumed pressures of the working fluid in these chambers 210 and 212 with respect to the angular disposition of the shaft 108. The solid line curve represents the pressure in the working chamber 210, while the dotted curve represents the pressure of the working fluid in the interior chamber 212.

As noted above, in actual operation the engine 70 is usually connected in tandem with at least one other similar engine unit. As shown in FIG. 42, two engines 70 are mounted side-by-side on a common shaft 255. Each of the engines 70 includes a manifold end plate and valve plate similar in structure to end plate 88 and valve plate 90 described hereinabove. However, of course, the ports in these valve plates are not in alignment and the operation of the two engines are out of phase. An end plate, not shown, is disposed between the two engines 70 so as to separate the cylindrical chambers 80 of the engines.

It should also be recognized that, of course, the engine 70 could be operated as a four-cycle engine, i.e. the assemblies 132 and 133 rotate through an angle of 120 during each complete cycle of operation. However, obviously if the engine 70 were to be operated as a four-cycle engine, the valve plate 90 could be replaced by a pair of diametrically opposed inlet valve means 257 and a pair of diametrically opposed outlet valve means 259 positioned on the center housing 76. Such a modification, however, is believed to be within the skill of the art, and, for this reason, is not described in detail herein. Furthermore, when the engine 70 is operated as a four-cycle engine, the interior chamber is

obviously not required to be used to pre-compress the working fluid.

FIGS. 53-60 illustrate diagrammatically the relative positions of the components of the engine 70 when the engine functions as a four-cycle engine. When the components of the engine 70 are as shown in FIG. 53, the working fluid is just beginning to be drawn into the working chamber 210 through the inlet valve means 257 and the exhaust valve means 259 are closed. When 5 the components of the engine 70 have rotated to the position shown in FIG. 54, working fluid is still being drawn into the working chamber. However, when the components of the engine 70 have rotated to the position shown in FIG. 55, the inlet valve means 257 has 10 been closed and the compression of the working fluid in the working chamber 210 is beginning. This compression of the working fluid in the working chamber continues while the components of the engine rotate to the position shown in FIG. 56. Thereafter, when the 15 components have rotated to the position shown in FIG. 57, ignition of the compressed working fluid in the working chamber 210 occurs. Ignition and expansion of the working fluid in the chamber 210 continues as the components of the engine 70 rotate to the position 20 shown in FIG. 58.

When the components of the engine 70 have rotated to the position shown in FIG. 59, the exhaust valve means 259 are opened and the working fluid in the working chamber is initially connected with the exhaust. While the components of the engine are rotated from their FIG. 59 position in their FIG. 60 position, the working fluid in the working chamber 210 continues to be exhausted from the working chamber. As the components of the engine rotate from their FIG. 60 position to the position shown in FIG. 53, the exhaust valve means 259 is closed and inlet valve means 257 is again opened.

FIG. 62 illustrates graphically the various phases of operations during a cycle of operation, with respect to the angular position of the shaft 108, when the engine 70 is functioning as a four-cycle engine. In FIG. 62, the outer ring 261 represents the phases during the first half of the cycle, i.e. during the first 360° of rotation, while the inner circle 263 represents the phases of operation during the second half of the cycle, i.e. during the second 360° of rotation.

FIG. 63 illustrates the principle by which the rotary engine 70 operates. The relative magnitude and direction of the forces created by working fluid in the chamber 210 are diagrammatically shown by the arrows generally indicated by the reference number 265. These fluid pressure forces 265 acting on the curved surfaces 146 of the rotary assemblies 132 and 133 result in a pair of net, radially inwardly directed resultant forces 55 shown at 266 and 267. The lines of action of these resultant forces 266 and 267 pass through the axes 4 and 5 of rotation of the rotary assemblies 132 and 133 which, as noted above, are eccentrically spaced from the longitudinal central axis 6 of the cylinder 80. Since 60 the lines of action of the resultant forces 266 and 267 pass through the axes 4 and 5, no force moment or couple is obtained on the rotary assemblies 132 and 133. It is seen, however, that the fluid pressure forces 265 acting on the exposed planar radial surfaces of each of the rotary assemblies 132 and 133 are unbalanced and therefore produce a couple or moment on each of the rotary assemblies around their respective axes of rotation. Of course, the effect of the moment at any given

angular position of the shaft 108 is dependent upon the surface area of the exposed planar radial surfaces of each of the rotary assemblies 132 and 133 which varies between maximum and zero. However, the momentum of the rotor assemblies 132 and 133 will carry the assemblies through the zero point. Furthermore, when two or more engines are coupled in tandem, as shown in FIG. 42, any problems in this regard are obviated.

FIGS. 67-76

While the rotor assemblies 132 and 133 and the slider assembly 158 are utilized in the rotary engine 70, other means could be utilized to accomplish the function of these assemblies in this engine. In this regard, a rotor assembly might be designed which would accomplish the functions of both the assemblies 131 and 132 and the assembly 158. Such a rotor assembly is diagrammatically shown at 270 in FIGS. 67 and 68.

The rotary assembly 270 includes a fixed base 272 and a pair of identical curved members 274 and 276. The one ends of the members 274 and 276 are pivotally connected at 278 and 280 to the opposite ends of the base 272. A generally T-shaped member 282 is pivoted at 284 to a relatively fixed member, such as the excenter member 120. The upper curved ends 286 and 288 of the member 284 extend beneath the other overlapping ends 290 and 292 of the members 274 and 276.

In FIG. 67, the rotor assembly 270 is shown in a position comparable to the position of the rotor assembly 132 in FIG. 38; whereas in FIG. 68, the rotary assembly 270 is shown in a position comparable to that of the assembly 132 in FIG. 44. By comparing the positions of the rotor assembly 270 in FIGS. 67 and 68, it is seen that as the assembly 270 rotates through an arc of 180°, the ends 290 and 292 of the members 274 and 276 move toward each other thereby increasing the amount they overlap the ends 286 and 288 of the member 284. In view of the construction of the rotor assembly 270, a pair of such assemblies are mounted in an engine so that their base portions 272 are always in surface-to-surface, sliding contact, thereby eliminating the need for a slider assembly, such as assembly 158.

In FIGS. 69 and 70, a rotor assembly 296 is diagrammatically illustrated. The assembly 296 is substantially structurally and functionally identical to the assembly 270 except that the ends 286 and 288 of the member 284 overlap the ends 290 and 292 of the members 274 and 276 instead of vice versa as in assembly 270.

In FIGS. 71 and 72, another modified rotor assembly 300 is diagrammatically illustrated. The assembly 300 includes a base 302 which is pivotally connected, at 304 and adjacent to its center, to a relatively fixed member, such as the excenter member 120. The relatively flat outer portions 306 and 308 of the base 302 are positioned in a plane which always extends through the central longitudinal axis of the cylindrical chamber 310 in which assembly 300 rotates. A pair of curved members 312 and 314 are pivotally connected at 316 and 318, respectively, to the end of the portions 306 and 308, respectively, of the base 302. The ends 320 and 322 of the members 312 and 314, respectively, overlap each other at all times. The members 312 and 314 are disposed in an annular groove 324 which extends about the periphery of chamber 310. The groove 324 guides or defines the path of movement of the members 312 and 314. FIG. 71 illustrates the position of the assembly 300 when it is located in a position comparable to that of the assembly 132 in FIG. 38;

whereas, FIG. 72 illustrates the position of the assembly 300 when it is in a position comparable to that of the assembly 132 in FIG. 44. The principle difference in the assembly 300, as it is shown in FIGS. 71 and 72, is the difference in the amount of the overlap between the ends 320 and 322 of the members 312 and 314. Again, no slider assembly is required when two rotor assemblies 300 are utilized in an engine since sealing, surface-to-surface contact is maintained between the adjacent portions 306 and 308 of the bases 302.

FIGS. 73 and 74 illustrate diagrammatically still another rotor assembly 328 which might be used with an improved rotary engine of the present invention. The rotor assembly 328 is generally similar in structure and mode of operation to the assembly 270 except that the side members 330 and 332 are straight rather than being curved like comparable members 274 and 276. Similarly, the ends 334 and 336 of the generally T-shaped member 338 are straight rather than being curved. Moreover, the members 330 and 332 are rigidly secured to the ends of the base 272 rather than being pivotally connected as at 278 and 280 in the assembly 270. The member 338 is constructed so that its ends 334 and 336 always fit within the members 330 and 332, respectively, and so that there is sliding, surface-to-surface contact between ends 334 and 336 and the members 330 and 332, respectively. FIG. 73 illustrates the assembly 328 in a position comparable to that of the assembly 270 in FIG. 67, while FIG. 74 illustrates the position of the assembly 328 comparable to that of the assembly 270 in FIG. 68.

FIGS. 75 and 76 diagrammatically illustrate still another rotor engine of the present invention. The assembly 340 is structurally and functionally identical to the assembly 328 except that the ends 334 and 336 of the member 338 are positioned so that the members 330 and 332 always fit therebetween. Moreover, as in assembly 328, there is sliding, surface-to-surface contact between the member 330 and end 334 and between the member 332 and end 336 in the assembly 340. FIG. 75 illustrates the assembly 340 in a position comparable to the position of assembly 328 in FIG. 73, while FIG. 76 illustrates the assembly 340 in a position comparable to the position of assembly 328 in FIG. 74.

CONCLUSION

In view of the foregoing, it should be apparent to those skilled in this art that the invention described herein provides a significant breakthrough in the rotary engine field. Moreover, because it is believed that the principles of the invention have broad applications, the term "engine" has been used herein for a generic sense so as to include all types of rotary engines, such as motors and compressors.

It should also be apparent to those skilled in the art that various other modifications of the components of engines described herein are possible. Thus, the preferred embodiments described herein are therefore to be considered in all respects as illustrative and not restrictive. The scope of the invention is indicated by the appended claims, rather than by the foregoing descriptions, and all changes which come within the meaning and range of equivalency of the claims herein are therefore intended to be embraced therein.

What is claimed is:

1. An improved balanced, rotary engine having a cycle which includes the four phases of intake, compression, expansion and exhaust, the engine compris-

ing:

housing means including at least one outer body, a cylinder wall in the housing body defining a generally cylindrical chamber in the outer body, and plate members which are adapted to close the ends of said cylindrical chamber;

said cylindrical chamber having a central, longitudinal axis and being comprised of at least two inter-communicating, coplanar, substantially, identical sub-chambers, said sub-chambers each having a center axis which is parallel to said longitudinal axis and having, in a plane perpendicular to said longitudinal axis, a sector-shaped cross-section, with said sector radii of said sub-chambers being of equal length, and with said center axes of said sub-chambers being equi-spaced from each other about said longitudinal axis and being equally eccentrically spaced from said longitudinal axis a distance less than the length of said sector radii;

rotor means including at least two, substantially, identical rotors positioned in said chamber and adapted to rotate in said chamber in a plane perpendicular to said longitudinal axis, with the number of rotors in said chamber being equal to the number of said sub-chambers, and with a rotor being mounted in each of said sub-chambers so that the rotor may rotate in said chamber about the said center axis of said sub-chamber and may move with respect to the other rotors in said chambers; each of the rotors including a wall portion that has a leading end, a trailing end, and a curved, radially outwardly directed surface which is positioned adjacent to the cylinder wall of the housing when the rotor is mounted in said chamber, with the radius of curvature of said curved surface being substantially equal to said sector radii, and the center of curvature of said curved surface coinciding with said center axis in said sub-chamber in which the rotor is mounted whereby a variable volume working chamber is defined between said curved surfaces of the rotors and the cylinder wall of the housing during rotation of the rotors in said chamber;

means for selectively permitting ingress and egress a working fluid into and out of said working chamber; and

means for preventing working fluid in said working chamber from passing radially inwardly from said working chamber, between the wall portions of adjacent pairs of rotors, to the interior of said chamber during rotation of the rotors in said chamber.

2. The improved rotary engine described in claim 1 wherein power shaft means extends through said chamber and through an aperture in at least one of the plate members; wherein the longitudinal axis of the shaft means coincides with said longitudinal axis; and wherein the shaft means is operatively connected with the rotors and rotates therewith.

3. The improved rotary engine described in claim 1 wherein working fluid seal means is positioned between the sides of the curved wall portions of the rotors and the members adjacent to the sides of the curved wall portions for forming a seal therebetween as the rotors rotate in said chamber; and wherein the curved surface of the wall portion of each rotor is continuous between the leading and trailing ends thereof.

4. The improved rotary engine described in claim 1 wherein the radius of curvature of said curved surfaces

of the rotors are substantially equal to, but shorter in length than, said sector radii of said sub-chambers so that at least a portion of said working chamber exists between said curved surfaces and the cylinder wall regardless of the positions of the rotors with respect to the cylinder wall of said chamber and so that although the radial thickness of said working chamber varies as the rotors rotate, said working chamber is generally annular in shape about the periphery of said chamber.

5. The improved rotary engine described in claim 1 wherein the means for preventing working fluid from passing between the trailing and leading ends of the wall portions of adjacent pairs of rotors includes at least two assemblies which are positioned within said chamber so that an assembly is positioned between the leading and trailing ends of each of adjacent pairs of rotors; wherein each assembly extends between the trailing and leading ends of the wall portions of the adjacent pairs of rotors; and wherein the assemblies rotate with the rotors and move with respect to the wall portions of the rotors during rotation of the rotors in said chamber.

6. The improved rotary engine described in claim 5 wherein each assembly includes two members, each of which member have a first surface and a second surface thereon; and wherein during rotation of the rotors, said first surface of one of the members is in contact with the wall portion of one of the pair of rotors, said first surface of the other member is in contact with the wall portion of the other of the pair of rotors and said second surface of the one member is in contact with said second surface of the other member.

7. The improved rotary engine described in claim 6 wherein said first surfaces of the members are in relative sliding contact with the wall portions of the pair of adjacent rotors, adjacent to the leading and trailing ends thereof; wherein said second surfaces of the members are in sliding contact with each other; and wherein during rotation of the rotors in said chamber, said sliding contact between said second surfaces of the members is in a plane including said longitudinal axis.

8. The improved rotary engine described in claim 7 wherein each assembly has bearing means between the members to facilitate sliding contact between said second surfaces of the members; wherein the bearing means rotates with the members and about said longitudinal axis; and wherein sealing means is disposed between said first surfaces of the members and the respective wall portions of the pair of adjacent rotors.

9. The improved rotary engine described in claim 7 wherein the radially inner ends of the members of each assembly are operatively connected with the radially inner ends of the members of each other assembly in said chamber; wherein sealing means is disposed between said first surfaces of the members and the respective wall portions of the pair of rotors; and wherein in each assembly, said second surfaces of the members are relatively flat and are in surface-to-surface sliding contact.

10. The unproved rotary engine described in claim 1 wherein said chamber includes an interior chamber spaced radially inwardly from said working chamber and defined in said chamber by the means for preventing working fluid from passing between the trailing and leading ends of the wall portions of adjacent pairs of rotors and by the wall portions of the rotors so that rotation of the rotors in said chamber causes the volume of said interior chamber to vary; and wherein valve means permit the selective ingress of working fluid into said

interior chamber and the selective egress of working fluid from said interior chamber to said working chamber during rotation of the rotors.

11. The improved rotary engine described in claim 10 wherein working fluid seal means segregates said working chamber from said interior chamber; wherein the second valve means selectively permits ingress of working fluid into said interior chamber when the volume of said interior chamber is relatively large and selectively permits egress of working fluid from said interior chamber when the volume of said interior chamber is relatively small so that said interior chamber acts to pre-compress working fluid therein.

12. The improved rotary engine described in claim 1 wherein the means for selectively permitting ingress and egress of working fluid includes at least one valve plate positioned adjacent to one end of said chamber.

13. The improved rotary engine described in claim 12 wherein the valve plate is positioned adjacent to the one side of the rotors and between the one side of the rotors and one of the plate members; and wherein the one plate member includes inlet and exhaust manifold means for cooperation with the valve plate.

14. The improved rotary engine described in claim 13 wherein the valve plate rotates with the rotors and about said longitudinal axis so that relative, radial movement occurs between the rotors and the valve plate during rotation thereof; and wherein working fluid seal means are positioned between the one sides of the rotors and the adjacent side of the valve plate for forming a dynamic seal therebetween.

15. The improved rotary engine described in claim 1 wherein said chamber includes at least three sub-chambers; and wherein at least three rotors are positioned for rotation within said chamber.

16. The improved rotary engine described in claim 1 wherein said chamber includes at least four sub-chambers; and wherein at least four rotors are positioned for rotation within said chamber.

17. The improved rotary engine described in claim 1 wherein said chamber includes a first and a second sub-chamber; and wherein a first and a second rotor are positioned in said chamber, with the first rotor being positioned in said first sub-chamber for rotation about the center axis of said first sub-chamber and with the second rotor being positioned in said second sub-chamber for rotation about the center axis of said second sub-chamber.

18. The improved rotary engine described in claim 17 wherein the radius of curvature of said curved surfaces of the first and second rotors are substantially equal to, but shorter in length than, said sector radii of the first and second sub-chambers so that at least a portion of said working chamber exists between said curved surfaces and the cylinder wall regardless of the positions of the first and second rotors with respect to the cylinder wall of said chamber and so that although the radial thickness of said working chamber varies as the rotors rotate, said working chamber is generally annular in shape about the periphery of said chamber.

19. The improved rotary engine described in claim 17 wherein said working fluid is a combustible gaseous mixture; wherein said chamber includes an interior chamber spaced radially inwardly from said working chamber and defined in said chamber by the means for preventing working fluid from passing between the trailing and leading ends of the wall portions of the first and second rotors and by the wall portions of the rotors

so that rotation of the first and second rotors in said chamber causes the volume of the interior chamber to vary; and wherein valve means permit the selective ingress of working fluid into said interior chamber and the selective egress of working fluid from said interior chamber to said working chamber during rotation of the first and second rotors.

20. The improved rotary engine described in claim 19 wherein working fluid seal means segregates said working chamber from said interior chamber; wherein the second valve means selectively permits ingress of working fluid into said interior chamber when the volume of said interior chamber is relatively large and selectively permits egress of working fluid from said interior chamber when the volume of said interior chamber is relatively small so that said interior chamber acts to pre-compress working fluid therein.

21. The improved rotary engine described in claim 17 wherein the means for preventing working fluid from passing between the trailing and leading ends of the wall portions of the first and second rotors includes a first and second assembly positioned within said chamber for rotation therein, with the first assembly being positioned adjacent to the one set of leading and trailing ends of the first and second rotors and with the second assembly being positioned adjacent to the other set of leading and trailing ends of the rotors; wherein the first and second assemblies extend between the wall portions of the first and second rotors and move with respect to the wall portions during rotation of the rotors in said chamber; wherein each of the first and second assemblies includes two members, with each of which members having a first surface and a second surface; and wherein for each of the first and second assemblies, said first surface of one of the members is in contact with the wall portion of the first rotor, said first surface of the other member is in contact with the wall portion of the second rotor and said second surface of the one member is in contact with said second surface of the other member.

22. The improved rotary engine described in claim 21 wherein said first surfaces of the members are in relative sliding contact with the wall portions of the first and second rotors, adjacent to the leading and trailing ends thereof; wherein said second surfaces of the members are in sliding contact with each other; and wherein during rotation of the first and second rotors in said chamber, said sliding contact between said second surfaces of the members is in a plane including said longitudinal axis.

23. The improved rotary engine described in claim 22 wherein the first and second assemblies include bearing means between the members to facilitate the sliding contact between said second surfaces of the members; wherein the bearing means rotates with the members and about said longitudinal axis; wherein sealing means is disposed between said first surfaces of the members and the respective wall portions of the first and second rotors; wherein the radially inner ends of the members of the first assembly are operatively connected with the radially inner ends of the members of the second assembly adjacent to the longitudinal axis; and wherein said second surfaces of the members are relatively flat and are in surface-to-surface sliding contact.

24. The improved rotary engine described in claim 17 wherein working fluid seal means is positioned between the sides of the curved wall portions of the first

and second rotors and the members adjacent to the sides of the curved wall portions for forming a seal therebetween as the rotors rotate in said chamber; wherein the curved surface of the wall portions of the first and second rotors is continuous between the leading and trailing ends thereof; wherein power shaft means extends through said chamber and through an aperture in at least one of the plate member; wherein the longitudinal axis of the shaft means coincides with said longitudinal axis; and wherein the shaft means is operatively connected with the rotors and rotates therewith.

25. The improved rotary engine described in claim 17 wherein the means for preventing working fluid from passing between the trailing and leading ends of the wall portions of the first and second rotors includes a first and second assembly positioned within said chamber for rotation therein, with the first assembly being positioned adjacent to the one set of leading and trailing ends of the first and second rotors and with the second assembly being positioned adjacent to the other set of leading and trailing ends of the rotors; wherein the first and second assemblies extend between the wall portions of the first and second rotors and move with respect to the wall portions during rotation of the rotors in said chamber; wherein each of the first and second assemblies includes two members, with each of which members having a first surface and a second surface; and wherein for each of the first and second assemblies, said first surface of one of the members is in contact with the wall portion of the first rotor, said first surface of the other member is in contact with the wall portion of the second rotor and said second surface of the one member is in contact with said second surface of the other member.

26. The improved rotary engine described in claim 25 wherein said first surfaces of the members are in relative sliding contact with the wall portions of the first and second rotors, adjacent to the leading and trailing ends thereof; wherein said second surfaces of the members are in sliding contact with each other; and wherein during rotation of the first and second rotors in said chamber, said sliding contact between said second surfaces of the members is in a plane including said longitudinal axis.

27. The improved rotary engine described in claim 26 wherein the first and second assemblies includes bearing means between the members to facilitate the sliding contact between said second surfaces of the members; wherein the bearing means rotates with the members and about said longitudinal axis; wherein sealing means is disposed between said first surfaces of the members and the respective wall portions of the first and second rotors; wherein the radially inner ends of the members of the first assembly are operatively connected with the radially inner ends of the members of the second assembly adjacent to the longitudinal axis; and wherein said second surfaces of the members are relatively flat and are in surface-to-surface sliding contact.

28. The improved rotary engine described in claim 26 wherein the means for selectively permitting ingress and egress of working fluid includes at least one valve plate positioned adjacent to one end of said chamber; wherein the valve plate is positioned adjacent to the one side of the rotors and between the rotors and one of the plate members; and wherein the one plate mem-

ber includes inlet and exhaust manifold means for cooperation with the valve plate.

29. The improved rotary engine described in claim 28 wherein the valve plate rotates with the rotors and about said longitudinal axis so that relative radial movement occurs between the rotors and the valve plate during rotation thereof; and wherein working fluid seal means are positioned between the one side of the rotors and the adjacent side of the valve plate for forming a dynamic seal therebetween.

30. The improved rotary engine described in claim 28 wherein working fluid seal means is positioned between the sides of the curved wall portions of the first and second rotors and the members adjacent to the sides of the curved wall portions for forming a seal therebetween as the rotors rotate in said chamber; wherein the curved surface of the wall portions of the first and second rotors is continuous between the leading and trailing ends thereof; wherein power shaft means extends through said chamber and through an aperture in at least one of the plate member; wherein the longitudinal axis of the shaft means coincides with said longitudinal axis; and wherein the shaft means is operatively connected with the rotors and rotates therewith.

31. The improved rotary engine described in claim 30 wherein said working fluid is a combustible gaseous mixture; wherein said chamber includes an interior chamber spaced radially inwardly from said working chamber and defined in said chamber by the means for preventing working fluid from passing between the trailing and leading ends of the wall portions of the first and second rotors and by the wall portions of the rotors so that rotation of the first and second rotors in said chamber causes the volume of the interior chamber to vary; and wherein valve means permit the selective ingress of working fluid into said interior chamber and the selective egress of working fluid from said interior chamber to said working chamber during rotation of the first and second rotors.

32. The improved rotary engine described in claim 31 wherein working fluid seal means segregates said working chamber from said interior chamber; and wherein the second valve means selectively permits ingress of working fluid into said interior chamber when the volume of said interior chamber is relatively large and selectively permits egress of working fluid from said interior chamber when the volume of said interior chamber is relatively small so that said interior chamber acts to pre-compress working fluid therein.

33. The improved rotary engine described in claim 31 wherein the first and second assemblies includes bearing means between the members to facilitate the sliding contact between said second surfaces of the members; wherein the bearing means rotates with the members and about said longitudinal axis; wherein said sealing means is disposed between said first surfaces of the members and the respective wall portions of the first and second rotors; wherein the radially inner ends of the members of the first assembly are operatively connected with the radially inner ends of the members of the second assembly adjacent to the longitudinal axis; wherein said second surfaces of the members are relatively flat and are in surface-to-surface sliding contact; wherein the valve plate rotates with the rotors and about said longitudinal axis so that relative radial movement occurs between the rotors and the valve plate during rotation thereof; wherein working fluid

25

seal means are positioned between the one side of the rotors and the adjacent side of the valve plate for forming a dynamic seal therebetween; wherein working fluid seal means segregates said working chamber from said interior chamber; and wherein the valve means selectively permits ingress of working fluid into said interior chamber when the volume of said interior chamber

26

is relatively large and selectively permits egress of working fluid from said interior chamber when the volume of said interior chamber is relatively small so that said interior chamber acts to precompress working fluid therein.
